(Continued)

Primary Examiner — Robin V Webster(74) *Attorney, Agent, or Firm* — Banner & Witcoff, Ltd.(57) **CLAIM**

The ornamental design for a utility wrap, as shown and described.

DESCRIPTION

FIG. 1 is a top, front perspective view of a utility wrap showing our new design;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof; and,

FIG. 8 is an enlarged view of the region identified in FIG. 7, shown in isolation.

The broken lines showing the remainder of the utility wrap represent unclaimed subject matter and form no part of the claimed design.

1 Claim, 8 Drawing Sheets# US D820,542 S
